UNITED STATES PATENT OFFICE.

VICTOR E. LINDFORS, OF BUTTE, MONTANA, ASSIGNOR OF ONE-HALF TO JACOB MAKI,
OF BUTTE, MONTANA.

WIRE-TWISTING DEVICE.

Application filed October 8, 1923. Serial No. 667,329.

To all whom it may concern:

Be it known that I, VICTOR E. LINDFORS, a citizen of the United States, residing at Butte, in the county of Silver Bow and State of Montana, have invented a new and useful Wire-Twisting Device, of which the following is a specification.

This invention relates to a wire twisting device, the primary object of the invention being to provide a device to facilitate the positioning and twisting of a wire employed for securing a hose or similar flexible conduit to a nozzle or splicing pipe.

A further object of the invention is to provide a twisting device of this character that may be employed for twisting and positioning a wire wherein the strands of wire may be secured in proximity with each other, or appreciable distances apart at the will of the operator.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an elevational view disclosing a wire twisting device constructed in accordance with the invention as in use.

Figure 2 is a front elevational view of the same.

Figure 3 is a front elevational view disclosing a modified form of the same.

Figure 4 is a sectional view taken on line 4-4 of Figure 1.

Figure 5 is a sectional view taken on line 5-5 of Figure 1.

Referring to the drawings in detail, the reference character 5 designates the threaded shank forming the body portion of the device.

The reference character 6 designates the handle portion of the device, which is employed for rotating the shank to operate the device in a manner to be hereinafter more fully described.

At the opposite end of the threaded shank 5 is the head 7 which is formed with an opening to receive the reduced end 8

of the shank which is formed with a circumferential groove 9 designed to receive transversely extended pin 10 positioned in the head 7 to permit of rotary movement of the shank within the head but at the same time prevent displacement of the shank.

Formed in the head 7 are angularly disposed wire receiving grooves 11 which grooves define hook members 12 and a central hook member 13, the hook members 12 having curved edges 14 to contact with the hose or article to which the wire is being secured in a manner to permit the device to be rocked in the final movement of the tool to tighten the wire.

As shown, the forward side edges of the head 7 are rounded as at 15 to allow the wire being bent, and which in the present showing is indicated at 16 to move over the edges of the head eliminating any possibility of the corners of the head cutting the wire during the positioning of the wire.

Disposed on the threaded shank 5 is a wire drawing member 17 provided with a base 18 which is in the form of a flange provided with cut out portions 19 extending from the side edges thereof, and terminating at points adjacent to the shank 5, where the cut out portions are formed with offset portions 20 for the reception of the wire being positioned.

In the use of the device lengths of wire having been bent upon themselves, are positioned on the hose, the ends of the wire pass through the loop formed by bending the wire upon itself as shown by Figure 2 of the drawings, the ends of the wire having been previously twisted together as indicated at 21 and shown more particularly by Figure 1 of the drawings.

The device is now positioned in a manner to cause the wires adjacent to the twisted portion 21 to enter the slots 19 whereupon a slight movement of the device to a position as shown in dotted lines in Figure 1 of the drawings, causes the wire to be bent downwardly and secured.

It might be further stated that when the device is positioned as shown by Figure 1, the handle portion 6 is rotated to cause the wire to be securely positioned on the hose prior to the bending of the wire in the final movement of the tool to secure the wire.

When the device is to be used for splicing

the ends of hose, the wire is positioned in such a way as to contact with the side faces of the head in a manner as shown by Figure 3 of the drawings, thereby holding the wires in spaced relation with each other as shown by Figure 3.

In this form of the invention a wire 22 is employed for holding the side portions of the wire in proper spaced relation with 10 each other.

I claim:

A wire twisting device including a threaded shank, a head swiveled on one end of the shank, said head having diagonally disposed 15 grooves formed in one surface thereof, said grooves defining lateral hook members and a central hook member, a wire drawing member movable on the threaded shank and having lateral slots, said slots adapted to re-

ceive a wire to secure a wire to the wire 20 drawing member, the diagonally disposed grooves adapted to accommodate wire sections to hold the wire sections in spaced relation, said head adapted to engage the article around which the wire is being positioned, and said wire drawing member adapted to move longitudinally of the threaded shank when the threaded shank is rotated to cause the wire to be tightened around the article on which the wire is being 25 positioned.

In testimony that I claim the foregoing as my own, I have hereto affixed my signature in the presence of two witnesses.

VICTOR E. LINDFORS.
